UNITED STATES PATENT OFFICE.

BENJAMIN E. GETZ, OF MORTON, ILLINOIS, ASSIGNOR TO A. F. MEYER MFG. CO., OF MORTON, ILLINOIS, A CORPORATION OF ILLINOIS.

GRAIN-ELEVATOR.

1,353,335.

Specification of Letters Patent. Patented Sept. 21, 1920.

Application filed October 18, 1918. Serial No. 258,726.

To all whom it may concern:

Be it known that I, BENJAMIN E. GETZ, a citizen of the United States, a resident of Morton, in the county of Tazewell and 5 State of Illinois, have invented new and useful Improvements in Grain-Elevators, of which the following is a specification.

This invention has reference to certain new and useful improvements in grain elevators.

One of the objects of the present invention is, to improve the construction of elevators which are built inside the crib, and particularly those which are called "one 15 side" elevators, viz.; those built on one side of the drive-way extending through the crib.

The invention has for a further object, to position the leg of the elevator on one side 20 of the drive-way through the crib, so that the material dumped into the chute leading to the elevator boot, will be delivered in a direction transversely to the direction of movement of the lower run of the elevator, 25 and between the opposite vertical runs of the elevating means.

Built in elevators have been of several forms: one including legs on either side of the crib driveway, the elevating means 30 traveling down one leg, across and beneath the driveway and up the other leg, the material to be elevated being dumped into a chute extending across the driveway and longitudinally of the lower run of the elevator; another including spaced legs located on one side of the driveway, the chute 35 for the material being disposed transversely of the drive-way and arranged to transfer material to the elevating means which travels up one leg and down the other; and still another and a much preferred form, comprising a single leg located on one side of the driveway of the crib, the elevating means traveling down one side of the leg 40 and up the other side, the chute being arranged transversely of the drive-way and transferring the material in the path of the elevating means. The elevating means in each of the various types of elevators mentioned, comprises chains and buckets, and therefore, when the grain, whether shelled or on the cob, is dumped into the chute, it is transferred immediately in the direction 45 of movement of the buckets which cut their way through the material picking up a load and conveying it to a discharge spout at the

upper end of the leg. The buckets cutting through the grain destroy quantities of the loose grain and shell a large portion from off the ears which is wasted. It is this 60 feature of loss which I overcome with the use of my improved elevator and its arrangement in the driveway of the crib.

That the invention may be more fully understood, reference is had to the accompanying drawings, in which:—

Figure 1 is a front elevation of my improved elevator, partly in section, a portion of the driveway of the crib being shown with a wagon in dotted lines preparatory 70 to dumping material into the chute;

Fig. 2 is an end elevation of Fig. 1, partly in section, the view looking through the driveway, with the elevator on the side;

Fig. 3 is an enlarged detail in section 75 showing the boot construction;

Fig. 4 is a cross-section as the same would appear if taken on the line 4—4 of Fig. 3;

Fig. 5 is a view similar to Fig. 4, showing a modified boot construction. 80

Like characters of reference denote corresponding parts throughout the figures.

1 designates the floor of the driveway of a crib, a wagon A being shown in dotted lines to give an idea of the arrangement of 85 the leg of the elevator on one side of the driveway, and the position of the wagon when dumping the material to be elevated and stored.

Extending transversely across the driveway and below the floor is a chute 2 into which the material in the wagon is dumped and by means of which the material is transferred to the boot of the elevator. Also arranged in the driveway, but to one side and beneath the floor of the crib and communicating with the discharge end of the chute is a pit 3 in which is located the boot of the elevator leg. 90

In the form in which the elevator is here 100 shown it comprises a single leg 4 provided with endless chains 5 adapted to travel up one side of the leg and down the other, passing over sprocket wheels 6 at the upper end of the leg, which are journaled on a shaft 7 105 having a sprocket wheel 8 adapted to receive power from any suitable source and in any suitable manner. The lower end of the leg 4 is joined to a boot 9 located in the pit 3. 110

The lower runs of the chains 5 pass over idler sprocket wheels 10 and around float-

ing sprocket rings 11, in the boot 9. Connecting the opposite sprocket chains 5 and suspended therebetween, at suitable intervals, are buckets 12, which have a scooping action in the boot 9 and between the sprocket rings 11, see Fig. 3. As shown in Fig. 3, the sprocket rings 11 are of such a diameter as to cause a spreading out of the lower runs of the chains 5, so as to enable 10 the buckets 12 to have a good sweep and scoop the material deposited in the boot 9. As shown, the material discharged from the chute 2 will pass through one of the sprocket rings 11 into the path of the buckets 12, permitting the buckets to scoop up 15 the material, whether loose grain or corn on the cob without cracking the grain or shelling it. When the material is discharged by the buckets at the top of the 20 leg it is received in a chute 13 and transferred to a hopper 14 on which is swiveled a suitable flexible spout 15 by means of which the material is distributed to proper bins in the crib.

25 As shown in the drawings, the up and down runs of the elevating chains 5 are immediately behind each other in a direction longitudinally of the drive-way of the crib, and the chute 2 therefore, in the driveway, 30 leads directly into the front of the boot.

Ordinarily, in constructions of this character, the material would be discharged into the side of the elevator leg and down upon the buckets, and the pressure of the material upon that being discharged from the chute, together with the pressure of the buckets in another direction, not only cracks 35 the shelled corn, destroying the same, but also shells the corn from the ear, wasting 40 it. All this is obviated by the use of the present construction.

The boot construction shown in Figs. 3 and 4 include a semi-spherical shaped receptacle 16 in which the floating sprocket 45 rings 11 are carried, one wall of which is cut away, as at 17, to receive the discharge end of the chute 2.

In Fig. 5 a modified form of boot is shown, the remainder of the structure being substantially as seen in Figs. 1 and 2. In this modified structure the receptacle, designated 18, is preferably rectangular in shape, one wall cut away to receive the chute 2. In place of the sprocket rings 11, 50 a pair of sprocket wheels 19, suitably spaced apart are journaled in the boot 9, said sprocket wheels being so placed as to spread the lower runs of the chains 5, the material being discharged into the receptacle 18 between the sprocket wheels 19 to be scooped 55 up by the buckets.

The construction of boot last described is a very suitable and efficient boot, and one which may be manufactured at the minimum cost.

What I claim is:

1. An elevator for the inside of a crib and adapted to be placed on one side of the drive-way through the crib, comprising a single leg, a boot for said leg including a 70 receiving receptacle, elevating chains adapted to travel up one side of said leg and down the other side thereof, buckets attached to said chains and suspended therebetween, the lower runs of the chains being 75 spread within the boot so as to extend laterally outwardly beyond each of the respective opposite sides of the flights of the chains in the leg and to provide an enlarged open space, and a chute leading into the 80 boot and adapted to discharge material thereinto between the spread portions of said chains.

2. An elevator for the inside of a crib and adapted to be placed on one side of the 85 drive-way through the crib, comprising a single leg, a boot for said leg including a receiving receptacle, elevating chains adapted to travel up one side of said leg and down the other side thereof, buckets at- 90 tached to said chains and suspended therebetween, idler wheels for said chains located adjacent the entrance of said chains in said receptacle, sprocket wheels suitably spaced from each other in the receptacle 95 around which said chains travel, said sprocket wheels being so located relatively to said idler wheels as to spread the lower runs of the chains in the boot, and a chute leading into the boot and adapted to dis- 100 charge material thereinto between the spread portions of said chains.

3. A crib elevator including a leg, a boot for the leg, an elevating chain in the leg having buckets thereon, means to spread the 105 lower flights of the chain laterally and outwardly beyond each of the respective opposite sides of the flights of the chain in the leg to provide an enlarged open space and means to discharge material into the 110 boot between said spread portions of the chain and in the said enlarged open space provided thereby.

4. A crib elevator including a leg, a boot for the leg, an elevating chain in the leg 115 having buckets thereon, means engaging the flights of the chain adjacent the lower ends of the flights to restrict outward lateral movement thereof, means below the restricting means to effect spreading movement of 120 the part of the chain within the boot laterally and outwardly beyond the respective opposite sides of the flights of the chain in the leg to provide an enlarged open space, and material delivery means discharging 125 into the boot between said spread part of the chain in the boot and in the said enlarged space provided thereby.

5. A crib elevator including a leg, a boot for the leg, an elevating chain in the leg 130

having buckets thereon, means to spread the lower flights of the chain laterally and outwardly beyond each of the respective opposite sides of the flights of the chain in the leg to provide an enlarged open space, and material delivery means having a discharge occurring at approximately the center

of said space and adjacent the lower end of the leg.

In witness whereof, I have hereunto affixed my hand this 8th day of October, 1918.

BENJAMIN E. GETZ.
